UNITED STATES PATENT OFFICE.

NATHAN H. EDGERTON, OF PHILADELPHIA, PENNSYLVANIA.

ELECTRIC-ARC LAMP.

SPECIFICATION forming part of Letters Patent No. 279,363, dated June 12, 1883.

Application filed January 30, 1883. (No model.)

To all whom it may concern:

Be it known that I, NATHAN HUNTERY EDGERTON, of the city and county of Philadelphia, in the State of Pennsylvania, have 5 invented certain Improvements in Electric-Arc Lamps, of which the following is a specification.

My invention relates to a class of electric-arc lamps in which the electrodes are in a vertical or nearly vertical position, in which the lower electrode is fixed and formed of refractory material, and in which the upper electrode is a carbon pencil so set as to rest during the time when it is not in contact with the 10 fixed electrode by its own weight upon detaining-pins of incombustible material which touch it a short distance to the rear of its extreme front end and arrest its gravitational action.

20 My invention embraces the provision of improved means of application for the carbon-detaining pins, and of a separate magazine or pencil-holder for the carbon pencils constituting the upper electrode, by the employment 25 of which not only are all devices used to hold the carbon pencil and known as carbon "clamps," "clutches," or "holders" dispensed with, but the utilization of the entire substance of each carbon point, and the continuous 30 automatic supply of carbons, calculated to enable the continuous running of the lamps for a predetermined period, enabled.

35 My invention, equally with that class of devices with which it is most nearly connected, utilizes the passage of an electric current through the lamp and the attraction of an electro-magnet energized thereby for an armature, to withdraw the upper electrode from the lower electrode and occasion the formation 40 of a suitable arc interval through which the current is set up. It likewise avoids all feed-shunting devices and insures a constant length in the arc interval, the feed of the upper electrode taking place by gravity just as rapidly as the electrode itself is consumed, and being, moreover, under such regulation as to render it impossible that said upper electrode should approach the fixed electrode more nearly than a predetermined distance 45 during the entire period of the passage of the current.

In the accompanying drawings, Figure 1 represents in central vertical sectional front elevation a preferred form of lamp conveniently embodying my invention. 55

Fig. 2 is a similar side elevational view of the same, representing however a modified form of carbon-feed tube.

Fig. 3 is a transverse sectional plan through said modified form of feed-tube, taken on the dotted line *x x* of said Fig. 2.

Fig. 4 is a sectional elevational detail of a form of fixed electrode.

Fig. 5 is a detail of the feed-tube follower.

Fig. 6 is a horizontal sectional plan taken 65 on a plane projected on the dotted line *y y* of Fig. 1, and,

Fig. 7 is a similar view on the dotted line *z z* of Fig. 2.

Similar letters of reference indicate corresponding parts.

In the drawings, *A* represents the casing for the electro-magnet, it being a box or cover suspended from a hanging frame *B*, and from which in turn is suspended the globe or bowl 75 *C* of the lamp. The casing is preferably cylindroform, and is composed of a metallic disk or head *a* to which is rigidly connected a depending cylinder of metal *a'* which constitutes its sides or walls. This depending cylinder is 80 preferably provided with an external circumferential flange *a''* by means of which, as a device permitting of ready connection, the casing is inclosed below by a base-plate *a'''* of insulating material, such for instance as ebonite, the 85 result of the application of which is that the casing becomes an inclosed drum, so to speak.

Connected in contact with the lower surface of the base-plate of the casing is what I term a "globe-plate" *D*, it being a disk of metal 90 against the under face of which the globe is fitted.

Connection between the cylinder of the casing the base-plate and the globe-plate is conveniently effected by means of the screws *E*, 95 and the removable application of the globe to the globe-plate by means of the hook-headed bolts *F*, all as clearly represented in Fig. 2.

G is a U-shaped suspender or support for the fixed electrode, the same being preferably 100 formed of solidified graphite and connected with the insulating base-plate of the casing by

screws *g* or kindred contrivances as represented in Fig. 1.

g is a socket vertically erected from the suspender *G* and designed to retain in fixed position the lower electrode *H*.

This lower electrode is formed of refractory substance, such, for instance, as graphite, iridium, or zirconium, and it may assume either the form represented in Figs. 1 and 2 or the form represented in Fig. 4, in the former instance the entire point or electrode proper being composed of incombustible material, while in the latter the electrode proper is formed as a coating or deposit on a former of metal or other conducting material which I have designated by *h* in said Fig. 4, and which is represented as spherical.

I is what I term the "carbon-feed tube," it being a vertically erected cylindric containing device or fixed magazine for containing the carbons constituting the positive electrode. It is supported in insulating-ferrules *i* which in turn are fixed in clamps *b* forming a part of the hanging frame.

The feed-tube passes vertically downward through and axially with respect to the casing and extends a certain distance down within the globe.

It has no contact with either the head or the base-plate of the casing or with the globe-plate, but derives its sole support from the hanging frame.

It is also of such longitudinal extent as to be adapted to contain two or more carbons of ordinary length, one above the other, which are free, so far as any devices connected with them go, to gravitate through it.

J is a lifting-sleeve, it being a tube of sufficiently larger interior diameter to freely although closely surround the feed-tube, and to be capable of a vertical movement with respect thereto. At its lower extremity this lifting-sleeve is formed into or provided with a flanged collar *j*, preferably of brass, or of whatever material the lifting-tube is formed.

Fitted through this flanged collar are one, two, or a series of detaining-pins *K* of iridium, platinum, or kindred refractory material. These pins are preferably assembled in conically convergent relationship, and are designed to control and arrest the descent of the carbons from out the feed-tube.

The lifting-sleeve passes through openings in both the head and base plate of the casing and also in the globe-plate, and is both electrically and mechanically connected to the carbon-feed tube through the instrumentality of a stud or studs *d* projected from said feed-tube and passing through a slot or slots *k* in the sleeve, while at its lower extremity it is slightly prolonged beyond the lower extremity of said feed-tube, as represented in Fig. 2.

In Fig. 2 I have represented a slightly modified construction of carbon-feed tube in which a lateral enlargement is made at its upper portion, the object of which is to enable the placing of two carbons side by side in said upper

portion of the tube. The enlargement, midway of the tube, contracts by means of an inclined surface into the unenlarged lower portion of the tube, so that the exterior carbon contained in the enlargement is deflected by said inclined surface into said unenlarged lower portion when the other carbons have descended to give place to it.

L are spools connected together by means of a yoke *O* suitably affixed to the head of the casing.

P is a positive terminal applied to the casing preferably upon its flange, and *N* is a negative terminal similarly applied.

W is a wire led off from the positive terminal to which the line-wire of the exterior circuit is attached and wound around the spools in succession to form the coils *M*, the extremity of which wire beyond the last spool is conducted through a slot or opening *q* in the lifting-sleeve to the feed-tube to which latter it is firmly connected.

R is a wire or other electrical connection between the suspender *G* and the negative terminal *N*.

S is an armature of soft iron rigidly, although adjustably, connected with the lifting-sleeve at a point within the casing, horizontally disposed with respect to the poles of the electro-magnet, and within the area of influence of said poles.

T is a metallic plug or follower which is conformed to the interior of the carbon-feed tube, and is connected therewith by a flexible wire *t*. This follower is put in place upon the top of the last carbon and is adapted to gravitate with the latter through the tube, carrying its flexible wire in after it. When the carbons are exhausted the follower will be at the bottom of the tube, and is to be withdrawn by its wire so as to clean the tube of dust. This follower, in addition to subserving the purpose of cleaning the feed-tube, insures electrical connection between the carbons and the tube. The follower is adapted for use with a tube of the same diameter throughout.

U, Figs. 1 and 7, are two pieces or plates of graphite or other material of high electrical resistance, superimposed upon or otherwise applied to the base-plate of the casing, and extending from points below the armature respectively to the positive and negative terminals, the arrangement being such as, in the event of an accidental stoppage in descent of the carbon and consequent interruption of flow through the arc interval, to occasion the setting up of the current through the plates and armature (together constituting a circuit of high resistance) and so completely through the lamp without causing an interruption in the running of other lamps upon the same circuit, although the lamp in question be out of action.

Having now described a preferred form of apparatus conveniently embodying my invention, its operation is as follows:—

Assume the carbon-feed tube supplied with

a suitable number of carbons calculated to supply the lamp for a predetermined time, and further assume the lamp in connection with the line-wires of an electrical circuit through which for the time being no current is being passed:—under the above circumstances the lifting-sleeve, by its own weight and subject only to the restraint of its stud-and-slot connection with the feed-tube, has descended to the limit of its downward movement, and has, of course, carried down with it its armature, while the advance carbon electrode has gravitated through the feed-tube until its front extremity has encountered and rested upon the fixed electrode.

In this position of parts the set of the detaining-pins is predetermined to be such as to bring them just in contact with the carbon.

The result now of passing a current through the circuit of which the lamp forms part, is, primarily, to energize the magnet within the casing and so to occasion the attraction of the armature to it. The lift of the armature, however, occasions the lift of the lifting-sleeve, and, through the instrumentality of the detaining-pins, of the carbon or upper electrode.

This lift of the sleeve is determinable by the set of the armature upon it, which set is such as to provide a space between the poles of the magnet and the armature equal to the desired length of arc interval.

The instant that the electrodes are separated the light is established and continues as a practically constant quantity, the arc interval remaining uniform so long as the current continues to pass,—it being impossible so long as the detaining-pins remain and so long as the armature is under the influence of the magnet for the movable electrode to approach more nearly to the fixed electrode than a predetermined distance.

It will be readily perceived that so soon as one carbon is consumed a succeeding carbon replaces it, so that the supply is practically constant.

Upon the discontinuance of the current through the line-wires the armature is released, and, together with its lifting-sleeve and the upper electrode, descends until the two electrodes meet, or until the armature rests upon the plates of graphite and so establishes a shunt-circuit of high resistance, as hereinbefore explained.

In Fig. 1 I have represented the slot *q* in the lifting-sleeve as oblique, it being an expedient of manufacture to form, as it were, a bearing for the lifting-sleeve which will thus resist endwise thrust of the latter possibly resulting from the vibration of a floor from which the lamp is suspended.

It has however the further advantage that, occasioning as it does a partial rotation of the armature away from the poles of the magnet during its downward movement and its resting in such partially-rotated position, the initial attraction of the energizing-magnet upon the armature will be greater and will there-

fore occasion the more immediate and forceful lifting of the armature than if the latter were in a right line below the poles.

While I have described and represented pins, strictly as such, as a detaining device against which the conical extremity of the upper electrode bears and which arrest its gravitational action, it is yet competent for me to employ knife-edges, points of various kinds, small plates, or even a conical collar, as a substitute for these pins, it being, of course, understood that any such substitute contrivances are to be made of incombustible material and are to be set to touch the carbon pencil at a point intermediate between the apex and the base of its conical extremity.

I have both illustrated and described my lamp as having its electrodes in a vertical position, and in such position the best results are to be obtained.

It is proper, however, for me to state that it would be possible to place the entire device constituting my lamp in a horizontal position, and by the application of a spring contrivance, or its equivalent, constantly feed the movable electrodes against the detaining-pins, the operation of the armature and lifting-sleeve remaining essentially the same,—and further that this arrangement, while devoid of the feature of a gravity feed of the movable electrode, would yet, as I regard it, be properly within the scope of my invention so far as the other elements and combinations going to compose it are concerned.

Incident to my invention as well as to other previously patented devices are the advantages that it enables the utilization of the entire current for illumination; that the lamp requires little attention; that the light is steady and not liable to constant fluctuation or occasional extinction; that, there being no base-plate for the lower electrode, there is but little shadow cast, and that the negative electrode being practically indestructible the point of light remains fixed, forming a focusing-lamp.

Having thus described my invention, I claim and desire to secure by Letters Patent:

1. In an electric-arc lamp in which a lower fixed electrode of irreducible material is combined with an upper movable electrode being a carbon pencil free to gravitate with respect to an arc interval between it and the fixed electrode until entirely consumed, a fixed magazine or carbon-feed tube which is adapted to contain a series of carbon pencils arranged to successively gravitate therefrom and which is uninfluenced as to its position in the lamp by the passage of the electric current, substantially as set forth.

2. In an electric-arc lamp, the following instrumentalities in combination, viz:—first, a fixed magazine or carbon-feed tube adapted to contain a series of carbon pencils so arranged as to successively gravitate therefrom; second, detaining-pins, points, or equivalent contrivances, adapted to arrest the gravitational ac-

tion of that carbon pencil which for the time being is the upper electrode by bearing against its conical front extremity; third, a carbon-lifting sleeve to which said detaining-pins are attached; fourth, an armature applied to said lifting-sleeve; and, fifth, an electro-magnet in the circuit of the lamp;—the arrangement being such that the setting up of a current in the circuit energizes the electro-magnet and there-
10 by occasions the attraction of the armature, the lift of the lifting-sleeve, and the consequent lift of a carbon electrode to a distance from the fixed electrode correspondent to the are interval desired, substantially as set forth.

15 3. In an electric-arc lamp of the class herein recited, the combination of a casing or kindred containing device inclosing an electro-magnet, a fixed magazine or carbon-feed tube adapted to contain a series of carbons arranged
20 to successively gravitate therefrom, a carbon-lifting sleeve independent of the magazine, and an armature upon said lifting-sleeve, the arrangement being such that upon the energizing of the magnet the armature is attracted
25 and the sleeve lifted with respect to both magazine and casing, substantially as set forth.

4. In an electric-arc lamp of the class herein recited, the combination of the carbon-feed tube, the lifting-sleeve, and the stud-and-slot

connection between said tube and sleeve, substantially as and for the purposes specified. 30

5. In an electric-arc lamp in which a lower fixed electrode of irreducible material is combined with an upper movable electrode being a carbon pencil free to gravitate with respect 35 to an are interval between it and the fixed electrode, the combination of two pieces or plates of graphite, positive and negative terminals of the line-wires with which the lamp is connected, and an armature adapted upon its unrestrained descent to rest upon said plates and complete a circuit of high resistance, substantially as and for the purposes set forth. 40

6. In an electric-arc lamp of the class herein recited, the combination of an electro-magnet in the circuit of the lamp, a fixed carbon-magazine, a carbon-lifting sleeve which is vertically movable with respect to said magazine, an armature directly attached to said lifting-sleeve, and suitable means for adjusting said 45 armature upon said lifting-sleeve, substantially as and for the purpose set forth.

In testimony whereof I have hereunto signed my name this 24th day of January, A. D. 1883.

N. H. EDGERTON.

In presence of—

J. BONSALL TAYLOR,
JOHN JOLLEY, JR.
